FREDERICK K. BLANCHARD, OF NEW ROCHELLE, NEW YORK.

NECKTIE.

Application filed December 26, 1925. Serial No. 77,802.

Neckties of the four-in-hand type, many years ago, were made without linings and were formed by folding and refolding a wide piece of silk fabric to produce a relatively narrow tie. A tie so made is formed with a number of folds or layers of fabric which give the tie thickness or body and add greatly to its attractiveness and durability. The silk fabric of the tie was cut on the bias

10 so that the completed tie was rendered longitudinally resilient, a feature that is very desirable in a necktie. Such ties are, however, very expensive to make owing to the large amount of silk fabric required to form them.

15 In order to cheapen their manufacture, four-in-hand ties are now formed of a piece of silk fabric of only sufficient width to form a tubular body of one thickness of fabric. This tubular body is lined for a portion of

20 its length with a strip of cheaper and more substantial fabric of approximately the shape of the finished tie, in order to give thickness to the tie. This lining is stitched along the central seam at the back of the tie.

25 Frequently a longitudinal pull upon the tie breaks this stitching and loosens the lining. The lining strip, owing to the manner in which it is secured within the body of the tie, frequently bunches at the knot-forming portion thereof and gives the tie a wrinkled appearance.

It is the main object of this invention to provide a scarf of the four-in-hand type which shall possess all of the advantages of 30 the single-piece, unlined, folded scarf and which shall be made up without the interposed lining and therefore will avoid all of the difficulties and disadvantages inherent in a lined, single folded tubular four-in-hand scarf.

Another important object and advantage of the invention is to economically and cheaply produce a scarf having all of the characteristics and advantages of a single-piece folded and re-folded scarf.

Another object of the invention is to provide a four-in-hand scarf the knot-forming portion of the body of which will consist of folded and re-folded bias cut fabric, the fabric folded within the outer layer or covering being formed of cheap material bias cut and stitched to the longitudinal edges of the main body of the scarf. Preferably the threads of the added material will run in 50 the same direction as the threads of the main body of the scarf and will be of substantially

the same resiliency and flexibility in order that the completed scarf shall have the feeling and other characteristics of a scarf made wholly and entirely of a folded and re-folded 60 single piece of bias cut fabric.

Another important object and advantage of this invention is that the meeting edges of the folded outer fabric are stitched together by loose stitches to permit the scarf 65 to stretch longitudinally without breaking the thread. This loose stitching is commonly known as slip stitching and it is performed by hand. At suitable points spaced apart along the seam the overlapping edges 70 of the fabric are strongly stitched together by several closely arranged stitches which are drawn tight and securely interlocked. The tight stitches are preferably formed with the same thread that is used for the loose or slip stitching so that the thread at suitable intervals along the seam is securely locked or tied to the fabric of the scarf, the seam being 75 loosely stitched together between the interlocked points. The purpose of this is to permit the scarf material to yield readily while at the same time should the thread be broken 80 the seam will not rip entirely, the ripping or breaking of the seam being confined to the space between two adjacent interlocked 85 points.

In the drawing, Figure 1 is a view of the inner side of the scarf with all of its parts unfolded;

Fig. 2 a view of the knot-tying portion of 90 the scarf and a portion of the neckband thereof showing the attached side wings folded in over the body of the scarf;

Fig. 3 a view similar to Fig. 2 showing 95 the final fold of one side of the knot-forming portion of the scarf;

Fig. 4 a view of the rear side or back of a complete scarf; and

Fig. 5 a detail sectional perspective view, 100 the section being taken through the knot-forming portion of the scarf.

Referring to the various parts by numerals, 1 designates the outer body portion of the scarf. This body portion is preferably formed of bias cut silk and is so shaped as 105 to provide a narrow neckband portion 2, and the flaring end portions 3 and 4 extending outwardly from the ends of the neckband portion. The flaring portion 3 is wider and slightly longer than the end portion 4 and is known as the knot-forming portion of the scarf. To the diverging, or outwardly ex-

tending, side edges 5 of the knot-forming portion of the scarf are permanently stitched side wings or extensions 6. These wings are of resilient or stretchable material, such as a thin woven fabric cut on the bias. These side wings preferably have substantially the same resilient characteristic as the body of the scarf. They are narrow at the ends adjacent the neckband portion of the scarf and gradually widen to their outer ends. They are stitched throughout their length to the edges of the body of the scarf by lines of stitches 7 so that said wings are permanently and firmly attached along one of their longitudinal edges to the body of the scarf. The side wings may be made of any suitable flexible resilient and comparatively soft fabric. The best result will be obtained by the use of a fabric having somewhat the characteristic of bias cut silk so that the scarf will have the feeling and appearance of being made up wholly of a single piece of bias cut silk fabric.

In folding the scarf to its final form the wings 6 are first folded inwardly against the inner side of the body of the scarf, one of said wings overlying the other as shown clearly in Fig. 2. A strip 8 of thin non-stretchable material is laid in the neckband portion of the scarf, as shown in Fig. 1. This strip is preferably cut on the straight so that it is non-resilient and will serve as a thin strengthening lining for the neckband. If desired this neckband strip 8 may extend into the smaller end of the scarf and serve as a lining therefor. Any suitable form of lining may be used for the smaller end of the scarf. It is manifest that, if desired, a side wing may be attached to one or both of the longitudinal edges of the smaller end of the scarf and said side wings may be folded in to give body and thickness to the smaller end of the scarf if desired. After the side wings have been folded in, as illustrated in Fig. 2, the body of the scarf is folded over to bring the outer longitudinal edges together at the center of the back fold of the scarf. In Fig. 3 one half of the body of the scarf, and one half of the neckband portion of the scarf is shown as folded to its final form. In Fig. 4 both sides of the body of the scarf are shown as having been folded inwardly to final form and stitched together, the meeting edges forming a longitudinally extending seam running substantially the entire length of the scarf. In the neckband portion of the finished scarf the front and back folds of the outer body or casing are stitched together by lines of stitches 9, said stitches running through the non-resilient reinforcing strip 8 to form a strong, thin and substantially non-stretchable neckband portion.

The overlapping edges of the body of the scarf which forms the longitudinally extend-

ing seam are stitched together loosely by means of a thread 10, said thread being preferably applied by hand sewing. At intervals along the seam the thread is firmly bound to the seam by a number of closely arranged tightly drawn stitches so that the seam thread is firmly locked to the fabric at intervals but is loosely stitched to the fabric in between the locked points. The points where the seam thread is locked to the fabric is indicated at 11 in Figs. 4 and 5.

A scarf made up in accordance with this invention will be soft and resilient throughout the knot-tying portion. The folded in side wings will have the same, or substantially the same, feeling and resiliency as the exterior silk fabric of the scarf. The side wings will follow the folds of the body of the scarf and will be doubled over upon themselves along the longitudinal edges of the finished scarf so that there will be no free edges and the liability of becoming displaced within the scarf will be avoided. Furthermore the folding over of the side wings along the longitudinal edges of the scarf will give to the scarf a full rich thick appearance along its edges, so that while the body of the scarf might be made of thin silk it will have the feeling and appearance of a heavy thick silk fabric. In the completed scarf the lines of stitches 7 are at the longitudinal center of the back of the scarf, as shown clearly in Fig. 5, so that the inner folded wings are permanently and tightly stitched to the outer fabric of the scarf at the longitudinal center of the back fold. This permanently holds the folded wings in position within the scarf while at the same time not interfering with or reducing the resiliency of the scarf because the wings and the body of the scarf, as hereinbefore stated, have substantially the same stretch or resiliency.

The thread 10 will not materially interfere with the resiliency of the back fold of the scarf, the loose stitches yielding to a longitudinal strain. Should the thread 10 be broken the interlocked stitches 11 will confine the ripping to the space between two interlocked points and will prevent the seam ripping throughout its length. This is important because in the ordinary scarf, where the seam is loosely stitched throughout its length when the seam thread is broken the entire seam will rip and the scarf will become unsightly if not entirely unfit for use.

What I claim is:—

1. A method of making a necktie, which consists in disposing a pair of fabric side wings along the opposite longitudinal edge of the knot-forming portion of the fabric outer body of the tie prior to the folding thereof with the inner longitudinal edges of the wings overlapping the opposite marginal edges of the said body; stitching to-

gether the said overlapping marginal edges of the body and side wings along their lengths; folding the said opposite marginal edges of the body rearwardly along longitudinal lines spaced inwardly from said stitching to dispose the side wings upon the inner face of the body; folding the body, and with it the side wings, rearwardly along longitudinal lines spaced inwardly from the first lines of fold; and connecting together the folded edges of the body by stitches to form a seam at the back of the tie.

2. A method of making a necktie, which consists in stitching a pair of lining pieces along one edge of each to the unfolded fabric outer body of the tie along the opposite longitudinal edges of its knot-forming portion; disposing said lining pieces to extend inwardly over the inner face of the body from their points of stitching; folding the body, and with it the lining pieces, rearwardly along longitudinally spaced lines; and connecting together the rearwardly folded edges of the body by stitching.

3. A necktie comprising an outer body formed of an elongated sheet of fabric folded into flat tubular form and having its opposite longitudinal edges stitched together to form a seam at the back of the tie; and a pair of lining pieces located within the knot-forming portion of the tie and each attached along one of its longitudinal edges to the said body adjacent the seam thereof, said lining pieces extending in opposite directions from said seam, around the interior

of the body, and covering the inner surface of the tubular knot-forming portion, the said lining pieces being unattached to the front portion of the finished tie.

4. A necktie comprising an outer body 40 formed of an elongated sheet of fabric folded into flat tubular form, the opposite longitudinal marginal edges of said sheet being folded inwardly and joined together to form a seam at the back of the tie; and 45 a pair of fabric lining sheets located within the knot-forming portion of the body and each stitched along one edge to one of said inturned marginal edges of the body, said lining sheets extending in opposite directions 50 from said back seam around the interior of the body, covering the inner surface of the tubular knot-forming portion and overlapping at the inner face of the front side of said portion along their longitudinal edges, the said overlapped longitudinal edges being free.

5. A folded scarf comprising a body portion 60 formed of fabric, the longitudinal edges of the body portion meeting in a seam extending longitudinally of the scarf at the back fold thereof, and a thread loosely connecting together said meeting edges, said thread at suitable intervals being permanently fixed to the fabric against reeving, the 65 loose stitches extending between the interlocked points.

In testimony whereof I hereunto affix my signature.

FREDERICK K. BLANCHARD.
